CONTINUOUSLY CHECKED COMMUNICATION SYSTEM

James W. Knapp, Brockport, and John C. O'Brien, Rochester, N. Y., assignors to General Railway Signal Company, Rochester, N. Y.

Application November 27, 1944, Serial No. 565,206

9 Claims. (Cl. 250—6)

1

This invention relates to radio telephone communication apparatus, and more particularly pertains to the inter-relation of a transmitting apparatus and its associated receiving apparatus located at a central station providing two-way communication between such central station and a distant station.

In radio communication systems employed in connection with the governing of traffic, such as on railroads and the like, it is considered desirable to provide means of checking the continued operativeness of the system by intermittently transmitting a checking signal from the central station to a distant station at which a suitable indication is displayed in the event that the checking signal fails to be received. In such a system, it is desirable that during regular transmission that this checking signal be removed, and that the cessation of the reception of such checking signal shall be immediately followed by proper voice communication, so that if the operator at the distant station fails to receive voice communication upon the cessation of the checking signal, he will be immediately advised that the communication system has failed. It is also desirable in a system employing the checking feature where the same carrier frequency channel is used for both directions of transmission, to cause the cessation of the checking signal transmission from the central station while the distant station is transmitting. This is because the transmission of the checking signal in such a case interferes with the proper reception of the message being transmitted from the distant station.

In view of the above considerations, it is proposed in accordance with the present invention to provide means at the central station responsive to the reception of a carrier from the distant station, to render the checking signal transmitting means ineffective and, at the same time to prevent the central operator from interrupting communication from the outlying station.

In radio communication systems of the above type which employ amplitude modulation of the carrier, it is conventional practice to provide automatic volume control means so that the reception from a distant station will remain substantially constant although the space transmitted signal may be subject to fading and the like. When an AVC system is employed, it is obvious that the receiver becomes extremely sensitive to the noise level of the location upon the cessation of the carrier signal being received. Thus, it is desirable to provide means for squelching or

muting the amplifier whenever a carrier is not being received and this means being so arranged as to require the reception of a carrier substantially above the noise level of the location before the amplifier is rendered active.

Therefore, another object of the present invention is to provide means which is controlled in accordance with the reception of a carrier signal of a substantial value above the surrounding radio noise level in such a way that such means may be employed both for interlocking the receiver of the central office with its associated transmitter, and also for the squelching or muting control of the amplifying system of such receiver.

A further object of the invention is to accomplish the above purposes and objects with a minimum amount of apparatus and in a manner that the means referred to shall be of a rugged and reliable type, such as an electromagnetic relay of substantial construction.

Other objects, purposes and characteristic features of the present invention will be in part obvious from the accompanying drawings, and in part pointed out as the description of the invention progresses.

In describing the invention in detail, reference will be made to the accompanying drawings in which like reference characters designate corresponding parts throughout the several views, and in which—

Fig. 1 illustrates in a diagrammatic manner the general organization and inter-relation of the radio transmitter and receiver apparatus employed at a central station as organized in accordance with the present invention;

Fig. 2 illustrates in a diagrammatic manner one form of the present invention as providing for the control of a squelch relay employed in the organization of Fig. 1;

Fig. 3 illustrates in a diagrammatic manner another form of the present invention as providing for the control of a squelch relay and employed in the organization of Fig. 1.

For the purpose of simplifying the illustration and facilitating in the explanation, the various parts and circuits constituting the embodiment of the invention have been shown diagrammatically and certain conventional illustrations have been employed, the drawings having been made more with the purpose of making it easy to understand the principles and mode of operation, than with the idea of illustrating the specific construction and arrangement of parts that would be employed in practice. Thus, the

2

various electron tubes and their elements as well as the various relays and their contacts are illustrated in a conventional manner, and symbols are used to indicate connections to the terminals of sources of electric current instead of showing all of the wiring connections to these terminals.

The symbols (+) and (−) are employed to indicate the positive and negative terminals respectively of suitable sources of direct current; and the circuits with which these symbols are used always have current flowing in the same direction. The symbol (B+) is used to indicate the positive terminal of a suitable direct current source for the so-called "B battery supply" of the electron tubes, it being assumed that the opposite terminal of such a source is connected to ground indicated by the usual convention. Similarly, the symbol (C−) is used to indicate the negative terminal of a suitable direct current source for providing the desired negative bias on the electron tubes, it being assumed that the other terminal of this source is also connected to ground. It is of course understood that these different B and C sources of potential may be provided by suitable batteries, or may be provided by the usual conventional power pack organization. Since it is desirable to employ an alternating current in connection with the present invention, the terminals connected to such a source of energy are designated by the legend "A. C. Supply." The supply of energy to the heater elements of the cathodes of the various electron tubes has not been shown, but is assumed to be conventionally arranged for continuous operation.

Referring to Fig. 1, a radio transmitting apparatus has been indicated by a dotted rectangle designated "Radio transmitter"; and the associated receiving apparatus has been indicated by another dotted rectangle designated "Radio receiver." Associated with the radio transmitter and receiver is a suitable antenna A which is normally connected through back contact 6 of relay R11 to the radio receiver, but is connected through front contact 6 to the radio transmitter when the relay R11 is energized or picked up. Similarly, a source of positive plate potential (B+) is supplied to the radio receiver through back contact 7 of relay R11 but when relay R21 is picked up, this (B+) is connected to the radio transmitter.

The relay R11 is intermittently energized by a circuit closed from (+), through the keying contact 8, front contact 9 of relay SQR, windings of relay R1, to (−). The relay SQR is normally energized in a manner later to be explained, so that upon each closure of the keying contacts 8, the relay R11 is energized until the keying contacts again open. For convenience in rendering the disclosure definite, the keying contacts are assumed to be closed for a half second every three-and-a-half seconds, but it is to be understood that this timing operation may be varied as desired in accordance with the checking characteristics of the system employed, it being sufficient for an understanding of the present invention to know that these keying contacts 8 operate intermittently and continuously at some predetermined rate. The operation of the keying contacts 8 can be accomplished in any suitable way, but is assumed to be by a suitable constant speed motor as indicated in the legend.

Each time the relay R11 is picked up, the radio transmitter is rendered effective, and since back contact 10 of relay R21 is closed, the "check-tone

generator" is effective to cause the proper control of the transmitter so that its carrier frequency is modulated with a predetermined tone. In other words, a modulated carrier is radiated from the antenna A for the time during which the relay R11 is picked up, which occurs intermittently under normal conditions until a voice message is to be transmitted.

In the event that the operator at the central station desires to transmit a voice message to some outlying station, he merely actuates the self-restoring button PB causing the energization of the relay R21. The opening of back contact 10 removes the check-tone generator from control of the transmitter and connects the microphone M. At the same time, front contact 11 of relay R21 is closed which supplies energy through front contact 9 of relay SQR to steadily energize the relay R11. This renders the radio transmitter active to transmit a carrier which will be modulated in accordance with the voice operation of the microphone M in the usual way. The energization of indicator lamp 15 through contact 16 of relay R11 indicates that the transmitter has been rendered active. When the operator has finished his message, he releases the button PB which is self-restoring so that the relay R21 is deenergized followed by the deenergization of the relay R11, and relay R11 is again dependent upon the operation of the keying contacts.

It is assumed that the receiver at the distant station is equipped in a manner such as disclosed in the prior Patent No. 2,280,420, granted April 21, 1942, to V. C. Chappell, so that upon the cessation of the intermittent reception of the check-tone signal, a suitable indication will be displayed and the loudspeaker rendered active. Thus, whenever the check-tone signal fails to be received, the operator at the distant station expects to hear a voice message. If there is no voice message received when the signal controlled by the check tone indicates the absence of a check tone, then the operator is advised that there is some fault in the communication system. Such an organization provides a check upon the entire system of communication between the central station and the distant station. In other words, any failure in the system, such as a failure in the microphone at the central station, a failure in the loudspeaker at the receiving station, or any failure at some intermediate point in the system, is immediately brought to the attention of the operator at the distant station.

In the event that the central station receiver is receiving a carrier from the distant field station, this carrier acts through apparatus, later to be described, to cause the deenergization of the squelch relay SQR. This opens front contact 9 rendering the keying contacts 8 ineffective, and also closes back contact 12 which renders the amplifying apparatus active so that the loudspeaker LS gives forth any voice message imposed upon the carrier being received. So long as this carrier continues to be received, the contact 9 is maintained open so that the keying contacts 8 cannot cause the energization of the relay R11 and thereby interrupt the operation of the receiving apparatus. Also, the open condition of front contact 9 prevents the closure of front contact 11 (as the result of manual actuation of the foot switch or push button PB) from effecting the interruption of the voice message then being received by a radio receiver. In this way, the radio transmitting and receiving apparatus is in-

terlocked through the medium of relay means, specifically shown as the relay SQR, which has the dual purpose of providing the interlock and also acting as the squelching or muting means for the radio receiver.

With reference to Fig. 2 of the accompanying drawings, it will be seen that a portion of the receiving apparatus of Fig. 1 has been shown in block form while the remainder has been shown in somewhat greater detail. The antenna A and ground G are of course connected to the input of a suitable radio frequency amplifier in a conventional manner. Assuming that the receiver is of the superheterodyne type, the radio frequency amplifier output operates through a first detector or mixer stage to supply an intermediate frequency which passes through an intermediate frequency amplifier to the input of the second detector stage of the receiver. This connection between the intermediate frequency amplifiers and the second detector is effected inductively in a conventional manner, the second detector stage being shown as having a twin-diode tube TD. The left-hand portion of the twin-diode TD is used for detection purposes and to produce a negative potential dependent upon the existence of a radio frequency carrier for controlling the control grid of a gaseous tube GT while the audio frequency component of the output of this left-hand portion of the twin-diode acts through the first and second stages of the audio amplifier including triode 1—AF and pentode 2—AF to control the loudspeaker LS.

The radio receiver is of course normally inactive insofar as the reception of a carrier is concerned, and, for reasons later explained, this condition removes the negative bias from the control grid of the gaseous tube GT so that its plate-cathode circuit is normally conductive and allows the flow of pulsating current from the secondary of the power supply transformer 14 through the squelch relay SQR. The current which flows in this circuit is of course pulsating direct current and its pulsations are somewhat smoothed out by the multiple connection of the condenser C7. This improves the operation of the direct current type of relay SQR.

Since the squelch relay SQR is normally energized while there is no carrier being received, the open back contact 12 disconnects the cathode of the amplifier pentode 2—AF from ground which in effect supplies a high negative bias on its control grid so that such tube is non-conductive with no current flow through its plate-cathode circuit including the primary of a coupling transformer for the loudspeaker LS.

Upon the reception of a radio carrier, such carrier is of course amplified in the radio frequency stage and acted upon in the first detector or mixer stage to produce a beat or intermediate frequency in the usual way so that such intermediate frequency will be amplified by the intermediate frequency stages of amplification to produce a substantial signal potential on the input of the second detector (the left-hand portion of the twin-diode TD). This beat frequency signal appears across the plate and cathode of the left-hand portion of the twin-diode tube TD and is rectified thereby producing a pulsating direct current potential across the condenser C2 proportional to the amplitude of the carrier signal. A resistor R1 in series with a condenser C3 and a resistor R2 in multiple therewith provides what may be termed a frequency filtering circuit so that the half cycles of beat frequency will be

filtered and the resulting negative potential at connection 13 will vary in accordance with the audio frequency modulations imposed upon the carrier frequency as well as including a direct current component directly proportional to the signal strength. A connection from terminal 13 is made through a radio frequency choke RFC, a condenser C4 and a resistor R3 to ground. The potential across resistor R3 in this circuit, varies in accordance with the audio frequency component of the negative potential at 13 because the condenser C4 acts to readily by-pass such audio frequency component but blocks any direct current. The desired proportion of the audio frequency potential across the variable resistor R3 is fed through the first stage of audio frequency amplification to the power amplifier in the usual way so that the loudspeaker LS reproduces the audio frequency or voice modulations of the radio frequency carrier.

In addition to the audio frequency component of the potential at terminal 13, there is a direct current component which varies in accordance with the amplitude of the radio frequency carrier and this direct current component is fed through resistors R4 and R5 to the control grid of the gaseous tube GT. The audio frequency component of the potential at terminal 13 is further filtered out of the control grid of the thyratron tube GT by the use of a condenser C5 connected to ground between the resistors R4 and R5. In other words, condenser C5 readily bypasses potentials of audio frequency.

When the negative potential supplied to the control grid of the gaseous thyratron tube GT is of a sufficient value, this tube GT is rendered non-conductive so that the squelch relay SQR drops away. It should be noted that this action takes place only during a half cycle in which there is no current flow through the plate-cathode circuit of the tube GT, because so long as there is current flow through such circuit, the control grid cannot obtain control of the tube. In other words, the inherent characteristics of this type of tube are that it remains conductive when once rendered conductive, until its plate potential is reduced substantially to zero at which time the control grid may then gain control of the tube if it is then biased sufficiently negative. This is the reason why an alternating current source of potential is employed in connection with the plate circuit of this tube. The value at which the control grid must be negatively biased can be varied by changing the normal negative bias on the secondary grid of this tube, and in this way the strength of the carrier signal which must be received before the receiver is actually rendered responsive to the reception of a voice message can be readily predetermined. Thus, any existing level of noise may be eliminated or squelched when there is no carrier above a predetermined value.

The second or right-hand portion of the twin-diode detector tube TD provides for automatic volume control. More specifically, a by-pass condenser C6 supplies a certain amount of the beat frequency potential from the intermediate amplifier to the plate circuit of the right-hand portion of this twin-diode TD, where it is rectified and produces a negative potential on the AVC circuit, which negative potential can be varied by the amount of negative bias applied to its cathode. This AVC circuit (automatic volume control circuit) is of the usual type and acts on the preced-

ing stages of the receiver so as to control the amplification of the carrier signal.

Thus, when the receiver ceases to receive a radio frequency carrier of an amplitude above that which is necessary to provide the desired operation of the receiver, the AVC circuit becomes automatically effective to render the receiver very sensitive. When this occurs, the receiver would act to reproduce the "electrical noise" surrounding its location, if it were not for the squelch control. But under such circumstance, the gaseous tube GT becomes conductive because of the absence of a negative potential on its control grid, and the squelch relay SQR is immediately picked up. In other words, the value of the negative bias required on the control grid of the gaseous tube GT to render it non-conductive is higher than the negative bias produced by the noise level of the particular location of the receiver even with the receiver in its most sensitive condition and with substantially no negative bias on the AVC circuit.

In this way it will be seen that the squelch relay SQR is controlled to be picked up whenever the receiver fails to receive a carrier signal above a predetermined value and then acts to render ineffective the power amplifier stage so that the loudspeaker is mute. This carrier controlled relay SQR also acts to render the associated radio transmitter ineffective to transmit the checking tone signals while the receiver is receiving a radio carrier above the selected amplitude. In this way the squelch relay SQR serves its dual purposes as explained above in connection with Fig. 1.

With reference to Fig. 3 of the accompanying drawings, it will be seen that a portion of the radio receiver of Fig. 1 has been shown in block form while the remaining portion of the receiver has been shown somewhat in detail. The antenna A and the ground connection G are of course connected to the input of the receiver in a conventional manner, with the antenna selection being made by the contact 6 of the relay R11 and the plate potential being selected through back contact 7 of relay R11 as described in connection with Fig. 1. The input to the radio receiver is assumed to be applied to a radio frequency amplifier the output of which operates through a first detector or mixer stage to supply an intermediate or beat frequency which passes through an intermediate frequency amplifier to the input of the second detector stage of the receiver. This connection between the intermediate frequency amplifier and the second detector is effected inductively in a conventional manner, the second detector stage being shown as the left-hand portion of a twin-diode tube TD. This left-hand portion of the twin-diode TD is used for detection purposes to provide the input to the audio amplifier and also to produce a negative direct current potential dependent upon the reception of a carrier for controlling what may be conveniently termed "the squelch control portion of the receiver." The right-hand portion of the twin-diode TD is used for providing the automatic volume control with a potential dependent upon the strength of the received carrier signal.

The radio receiver is normally inactive insofar as the reception of a carrier signal is concerned and, for reasons later explained, this results in the normally deenergized condition of the squelch relay SQR¹. The open front contact 12¹ of this relay SQR¹ disconnects the cathode of the second

audio amplifier tube 2—AF from ground which in effect supplies a high negative bias on the control grid of this tube 2—AF, so that this tube is non-conductive, i. e., there is no current flow through its plate-cathode circuit including the primary of a coupling transformer for the loudspeaker LS.

The first audio amplifier stage includes a tube 1—AF of the triode type while the second stage 10 of audio amplification includes the tube 2—AF of the pentode type.

In connection with the squelch control, two direct current amplifying tubes 1—SQ and 2—SQ of the triode type are employed to provide control of the energy supplied to the squelch relay SQR¹ depending upon the reception of a carrier of a substantial value above the average radio noise field intensity of the particular location.

Upon the reception of a carrier signal, it is of course amplified in the radio frequency stage 20 and acted upon in the mixer stage to produce a beat or intermediate frequency in the usual way well known to those acquainted with superheterodyne radio receivers. When the output of 25 the intermediate amplifier is applied to the left-hand portion of the twin-diode TD, it is rectified to produce a pulsating direct current potential across the condenser C2. A resistor R1 in series with the condenser C3 and a resistor R2 in multiple therewith provide what may be termed a radio frequency filtering circuit so that the half cycles of the intermediate or beat frequency will be filtered and the resulting potential at the connection 13 is varied in accordance with the audio 30 frequency modulations imposed upon the carrier. A connection from terminal 13 is made through a radio frequency choke RFC, a condenser C4 and a resistor R3 to ground. The potential across resistor R3 in this circuit is the 35 audio frequency component of the potential appearing at terminal 13 because the condenser C4 acts to readily pass such audio frequency component but blocks the flow of any direct current component. The resistor R3 is of the variable 40 type and acts as a manual volume control for the audio amplification, so that the desired proportion of the audio frequency potential appearing across the variable resistor R3 is fed through the first stage of audio frequency amplification 45 to the power amplifier in the usual way so that the loudspeaker LS reproduces the audio frequency or voice modulations of the carrier. It 50 may be noted here that the circuits for the heater elements of the cathodes have not been shown, it being assumed that they are continuously energized so that the tubes are ready for immediate operation.

The first audio stage is supplied with the usual plate potential from (B+) through a load resistor, and the bias on the grid of tube 1—AF is 55 produced by the resistor and condenser arrangement of the associated cathode. A coupling condenser C5 is provided between the first audio stage and the second audio stage which is connected to the loudspeaker LS in the usual way.

It is to be understood that any suitable audio amplifier organization may be employed, the particular thing to be noted is that normally the cathode of the tube 2—AF is disconnected from ground so that this tube becomes non-conductive and there is no current flow through the plate-cathode circuit. In this connection it should be noted that the (B+) supplied to the plate of this tube 2—AF could be selected through a front 70 contact of the relay SQR¹ instead of the ground

connection of the cathode, and still be within the scope of the present invention. The cathode ground connection is preferably selected, since there is a lower potential to be broken by the contact 12¹. In other words, the second audio amplifier stage is normally rendered inactive with the squelch relay SQR¹ deenergized.

In addition to the audio frequency component of the potential appearing at terminal 13, there is a direct current component which varies in accordance with the strength of the radio frequency carrier signal received, and this direct current component is fed through the resistor R6 to ground. This variable resistor R6 provides that any desired proportion of such direct current potential may be supplied through the filtering resistor 35 to the grid of the tube 1—SQ. A condenser C8 provides a by-pass to ground for any audio or radio frequency which has not previously been filtered out. This is so that the tube 1—SQ is controlled in accordance with the direct current component of the negative potential appearing at the terminal 13 which varies in accordance with the strength of the carrier received.

Normally, when there is no carrier being received, there is no negative potential applied to the control grid of the tube 1—SQ, so that the plate-cathode circuit of this tube is normally conductive and a current flows from (B+), through the resistors 36 and 37 and the plate-cathode circuit of the tube 1—SQ to ground. The current which flows in this circuit causes a potential drop across the resistors 36 and 37 in such a way as to cause a negative bias to be impressed upon the control grid of the rectifier tube 2—SQ so that its plate-cathode circuit is normally non-conductive. When a carrier is received and a negative potential is applied to the control grid of the tube 1—SQ, and this tube ceases to be conductive, there is no potential drop across the resistor 37 and the negative bias on the control grid of the rectifier tube 2—SQ, is reduced to the point where the tube allows a plate-cathode current as supplied from the secondary of the transformer 38. This current flows through the relay SQR¹ and causes its contacts to be picked up to render the second stage of the audio amplifier to be active for amplifying the modulations of the received carrier. It should be noted in this connection that a condenser C9 is used in connection with the relay SQR¹ to smooth out the pulsations of current in the relay circuit and provide the better operation of the relay current SQR¹.

It should be noted that a resistor 39 is connected between the resistors 36 and 37 to ground so that a normal bias is placed on the control grid of the tube 2—SQ when it is acting to rectify the alternating current applied to the relay circuit. It is also to be understood that the various values of the resistors and characteristics of the tubes should be selected in accordance with the best engineering practices for the particular embodiment of the invention, the illustration being shown only for the purpose of illustrating the principles of such an organization. Since the characteristics of the tubes and their associated control circuits should be properly designed to give a quick response of the relay SQR¹, this relay will readily act as a squelch control of the amplifier so that upon the cessation of a received carrier, the amplifier is immediately rendered inactive and the loudspeaker LS is muted.

It is also to be understood that this relay SQR¹ has a contact 91 which operates to inter-relate

the receiver with the transmitting apparatus as disclosed in Fig. 1.

With a radio receiver thus organized, the receiver ceases to act on the loudspeaker until a radio frequency carrier signal is received of a substantial intensity above the radio noise field intensity of the location of the receiver, and this takes place even though the receiver is constructed to have an automatic volume control to make the receiver sensitive to the weakest permitted signal.

Although the present invention has been shown as associated with a receiver organization assumed to be of the superheterodyne type for the reception of amplitude modulated carriers, it is to be understood that the principles of the present invention may likewise be applied to receivers for frequency modulated carriers. In such an organization, it is of course understood that there is no automatic volume control such as provided by the right-hand portion of the twin-diode TD, but that the volume of such a frequency modulated receiver is controlled by reason of what is conventionally termed a limiter stage. But even though a receiver for a frequency modulated carrier is employed, the principles of the present invention may still be applied thereto and provide advantageous features. This is because a receiver for a frequency modulated carrier becomes extremely sensitive to the radio noise level as soon as a carrier ceases to be received and the limiter stage ceases to be overloaded by the reception of such carrier. For this reason, a circuit organization for muting the amplifier and speaker is especially desirable, and the same functions of interlock with the transmitter are also desirable and useful for the same reasons previously explained. Therefore, it is to be understood that the present invention is contemplated as being useful in connection with receivers for either amplitude or frequency modulated carriers.

In brief, it may be stated that one of the principle characteristics of the present invention is the provision of relay means controlled in accordance with the reception of a radio frequency carrier signal of a strength or field intensity substantially above the radio noise level of the particular location, and such relay means acting to effect the functions and relationships set forth in detail above. In both forms of the invention, such relay means is controlled by a direct current voltage developed at the input terminals of a diode detector in proportion to the intensity of the received carrier independently of its modulation characteristics.

The use of such a relay for rendering the amplifier inactive when there is no carrier signal being received has the advantage that the relay acts to mute the amplifier and loudspeaker abruptly. The usual squelch circuit with its tube control acts gradually and there is a certain amount of distortion during this gradual cutting-off operation. Thus, the present invention avoids the distortion of this "threshold" condition. Also, the relay has the further advantage of saving power by rendering the final audio stage or power amplifier completely inactive.

Although the organization shown in Fig. 1 illustrates how a positive interlock is provided to prevent the central office operator from interrupting a message being received, it should be understood that in some applications of radio communication, it may be desirable that the central office operator shall be permitted to interrupt the reception of a message at any time for

11

the purpose of transmitting important instructions. This may be accomplished by connecting from front contact 11 to the left of contact 9 so that relay R11 can repeat the relay R21 irrespective of the condition of relay SQR. It should be understood that this change may be made within the scope of the present invention without in any way affecting the other features and characteristics of the invention.

The feature herein disclosed relating to silencing or squelching the audio portion of a radio receiver when no carrier signal is being received is claimed in the divisional application Ser. No. 742,010, filed April 17, 1947.

Having described a radio communication system embodied into two different forms as constituting the present invention, it is to be understood that these forms are selected to facilitate in the disclosure of the invention rather than to limit the number of forms which it may assume; and, it is to be further understood that various modifications, adaptations and alterations may be applied to the specific forms shown to meet the requirements of practice, without in any manner departing from the spirit or scope of the present invention.

What we claim is:

1. In a radio transmitting and receiving system wherein the transmitter intermittently transmits a carrier signal for checking communication with a distant station and wherein a transmitter at the distant station at times transmits a modulated carrier signal to said receiver which includes an audio amplifier for supplying the input to a loud speaker, a triode electronic tube in addition to said audio amplifier, a relay connected in the plate-cathode circuit of said tube and controlled by the current flow therein to govern the output of said audio amplifier, means for governing the negative bias on the control grid of said tube in accordance with the intensity of a received carrier signal to render said relay effective to mute said loud speaker when the received carrier ceases, and means acting when said relay is controlled by the reception of a carrier signal to allow the operation of said loud speaker and to also render the associated transmitting means ineffective to transmit said intermittent carrier signals.

2. In a radio transmitting and receiving organization, a transmitter acting automatically to intermittently transmit carrier signals for checking communication with a distant station, a multiple stage receiver associated with said transmitter, a grid controlled thyratron tube, relay means associated with said tube, a plate-cathode circuit for said tube including said relay means and a source of alternating current energy in series, a control circuit for the grid of said tube supplied with a negative bias by said receiver when a carrier signal is being received by the receiver to thereby render said thyratron tube non-conductive, and circuit means controlled by said relay means when deenergized for preventing the automatic operation of said transmitter to intermittently transmit said carrier signals.

3. In a radio transmitting and receiving organization, a transmitter acting automatically to intermittently transmit carrier signals for checking communication with a distant station, a multiple stage receiver associated with said transmitter and including a diode detector, a grid controlled thyratron tube, relay means associated with said tube, a plate-cathode circuit for said tube including said relay means and a source of

alternating current energy in series to thereby normally energize said relay means, a circuit for the control grid of said tube supplied with a negative bias in accordance with the intensity of a signal supplied to the input of said diode detector whenever a carrier signal is being received by the receiver to thereby render said thyratron tube non-conductive and cause the deenergization of said relay, and circuit means controlled by said relay means when deenergized for preventing said automatic operation of said transmitter to intermittently transmit said checking carrier signals.

4. In a radio transmitting and receiving organization, a transmitter acting automatically to intermittently transmit a carrier signal for at intervals checking communication with a distant station, a multiple stage receiver associated with said transmitter and including an audio amplifier for supplying the input of a loudspeaker, a grid controlled thyratron tube associated with said receiver, a direct current relay, a plate-cathode circuit for said tube including said relay and a source of alternating current in series to thereby normally energize said relay, a condenser for shunting said relay, a circuit for the control grid of said tube supplied with a negative bias by said receiver when a carrier signal is being received to thereby render said thyratron tube non-conductive and cause the deenergization of said relay, and circuit means controlled by said relay when energized for permitting the automatic operation of said transmitter to intermittently transmit checking carrier signals but rendering said audio amplifier inactive to thereby mute said loud speaker, said means acting to prevent said automatic operation of said transmitter when said relay is deenergized and at the same time acting to allow said audio amplifier to be active for reproducing the modulations of a received carrier signal.

5. In a radio transmitting and receiving organization, a transmitter acting to automatically transmit a carrier signal at recurring intervals for checking communication with a distant station, a multiple stage receiver associated with said transmitter and including a diode detector and an audio amplifier for supplying the input to a loud speaker, a multiple stage squelch system including a first and a second triode tube, circuit means for applying a direct current negative potential to the control grid of the first triode when a carrier signal is received by the receiver and supplies an input to said diode detector to thereby cause said first triode to be non-conductive when a carrier signal is being received, circuit means controlled by the normal plate current of said first triode while no carrier signal is being received for normally negatively biasing the control grid of said second triode beyond cut-off but changing the negative bias on said control grid of the second triode to a normal operating value when the plate-cathode circuit of said first triode becomes non-conductive, a plate-cathode circuit for said second triode including a relay and a source of alternating current, and circuit means acting to render said audio amplifier inactive when said relay is deenergized and also acting to stop said automatic operation of said transmitter when said relay is energized.

6. In a radio transmitting and receiving organization adapted to operate on the same radio frequency channel, a transmitter acting to automatically transmit a carrier signal at recurring

intervals for checking communication with a distant station, a multiple stage receiver associated with said transmitter and including a diode detector and an audio amplifier for supplying the input to a loudspeaker, a multiple stage carrier responsive system including a first and a second triode tube, circuit means for applying a direct current negative potential to the control grid of the first triode when a carrier signal is received by the receiver and supplies an input to said diode detector to thereby cause said first triode to be non-conductive when a carrier signal is being received, circuit means controlled by the normal plate current of said first triode while no carrier signal is being received for normally negatively biasing the control grid of said triode beyond cut-off but changing the negative bias on said control grid of the second triode to a normal operating value when the plate-cathode circuit of said first triode becomes non-conductive, a direct current relay, a plate-cathode circuit for said second triode including said relay and a source of alternating current, and circuit means acting to stop said automatic operation of said transmitter when said relay is energized, whereby the reception of a carrier signal between intervals of check-tone modulated carrier transmission renders the automatic operation of said transmitter ineffective to thereby allow continued reception of said carrier signal without interference.

7. In a radio transmitting and receiving organization, a transmitter normally acting to intermittently transmit a carrier signal at recurring intervals for checking communication with a distant station, manually operable means for rendering said transmitter effective to transmit voice messages and at the same time preventing the transmission of said checking carrier signals, a multiple stage radio receiver associated with said transmitter and adapted to receive carrier current signals over the same carrier frequency channel as employed by said transmitter, said receiver being normally effective to receive signals but rendered ineffective whenever said transmitter is either manually or automatically set into operation, a grid controlled gas discharge tube associated with said receiver, a direct current relay, a plate-cathode circuit for said gas tube including said relay and a source of alternating current, a circuit for the control grid of said tube normally having substantially no negative bias but being supplied by a negative bias when a carrier signal is received by said receiver to thereby render the plate-cathode circuit non-conductive, and circuit means controlled by said relay when deenergized for preventing either the automatic or the manual operation of said transmitter.

8. In a radio transmitting and receiving system, a radio transmitter normally acting to intermittently transmit a carrier signal at recurring intervals for checking communication with a distant station, manually operable means for at times rendering said transmitter effective to

transmit voice modulated carrier signals and at the same time preventing the transmission of said checking carrier signals, a multiple stage radio receiver associated with said transmitter and adapted to receive modulated carrier current signals over the same carrier frequency channel as employed by said transmitter, said receiver being normally effective to receive signals but rendered ineffective whenever said transmitter is either manually or automatically set into operation, a grid controlled triode tube associated with said receiver, a direct current relay, a plate-cathode circuit for said tube including said relay and a source of alternating current in series, a circuit for the control grid of said tube supplied with a negative bias in accordance with the reception of a carrier signal by said radio receiver to thereby control said relay in accordance with the reception of signals by said receiver, and circuit means controlled by said relay for preventing either the automatic or the manual operation of said radio transmitter during the reception of a signal by said radio receiver.

9. In a radio transmitting and receiving system, a radio transmitter normally acting to intermittently transmit a carrier signal at recurring intervals for checking communication with a distant station, manually operable means for at times rendering said transmitter effective to transmit voice modulated carrier signals and at the same time preventing the transmission of said checking signals, a multiple stage radio receiver associated with said transmitter and adapted to receive modulated carrier current signals over the same carrier frequency channel as employed by said transmitter, said receiver being normally effective to receive signals but rendered ineffective whenever said transmitter is either manually or automatically set into operation, a grid controlled triode tube associated with said receiver, a direct current relay, a plate-cathode circuit for said tube including said relay and a source of alternating current in series, a circuit for the control grid of said tube normally having a negative bias below the cut-off of said tube supplied by said radio receiver to thereby de-energize said relay, but said circuit having such negative bias removed during the reception of a carrier signal by said receiver to thereby cause the energization of said relay, and circuit means controlled by said relay when energized for preventing either the automatic or the manual operation of said radio transmitter.
